DESIGN FOR A CIGARETTE HOLDER

Adam Janusz, Port Byron, N. Y.

Application January 18, 1936, Serial No. 60,647

Term of patent 7 years

To all whom it may concern:

Be it known that Adam Janusz, a citizen of the United States, residing at Port Byron, in the county of Cayuga and State of New York, has invented a new, original, and ornamental Design for Cigarette Holders, of which the following is a specification, reference being had to the accompanying drawing, forming a part thereof.

The opposite side of the holder is plain.
I claim:

The ornamental design for a cigarette holder, as shown and described.

ADAM JANUSZ.
